FIG. 6.

MOUNTING OF WIRE-LIKE OR WIRED COMPONENTS PARTICULARLY FOR AUTOMATIC PRODUCTION

Alexander Rizo Rangabe, Denmead, England, assignor to The Plessey Company Limited, Ilford, England, a British company

Application June 14, 1957, Serial No. 665,865

4 Claims. (Cl. 198—153)

This invention has for an object to provide improved means by which cylinder-shaped or wire-shaped or wired components can be readily and expeditiously attached to tape-like carriers.

According to one aspect the invention provides a composite carrier strip which comprises two flexible tapes extending face to face and secured to each other at longitudinally spaced positions, so as to form, between consecutive points of attachment, collapsible pockets into which the components, or the wires or the like, can be inserted. These pockets will open for accepting or releasing the inserted parts when the strip is longitudinally compressed so that adjacent lines of attachment of the tapes are moved towards each other, while the pockets are closed to clasp the components or wires when a longitudinal pull is exerted upon the tapes. Thus when the composite carrier strip is arranged to travel in an on-edge position, the components, or the wire ends of the components, can be allowed to drop into the pocket at a position in which the carrier is "pushed together" axially so that the pockets are open. Whereafter a longitudinal pull will clasp the two walls of each pocket around the inserted object. The components can then be conveyed in the carrier while the same is moved on in a taut condition, and they will be released to drop at a discharge position at which the carrier, if necessary or desired after being turned over by 180° about its axis, is once more "pushed together."

In order to open and close the pockets as required, the carrier may, if only wire ends of small diameter engage the pockets, pass between the rollers of each of a plurality of suitably spaced pairs of feed-control rollers, a pair of, say, positively driven rollers being followed, at a short distance in the direction of tape movement, by a pair of non-driven rollers which are frictionally braked to open the pockets between the said two pairs of rollers, while a positively driven pair of rollers at a point beyond the braked rollers ensures closing of the pockets as soon as they pass the braked roller pair. The strips may consist of paper, textile, plastic, or other pliable material.

Where the components themselves, or parts of appreciable diameter, are to be accommodated in the pockets, the opening and closing of the pockets is preferably effected by pairs of gripping jaws, which grip the strip between adjacent pockets, one pair at either side of each loading or unloading position, the two pairs being then moved towards each other to open the pockets after they have gripped the strip, while after releasing the strip the jaws are withdrawn sufficiently to allow the passage of the loaded pocket from the loading position or the entry of the next loaded pocket into the unloading position.

The components may be stored when held by the pockets of the composite carrier strip or strips. The strip or strips with the components may for this purpose be wound on reels or folded in zig-zag fashion, and may in this state be inserted into a magazine, from which they can be withdrawn and fed to supply the component to a point or points in an automatic production line.

An example of the invention, as applied to automatic production, is schematically illustrated in Figure 1 of the drawing accompanying the provisional specification, while Figures 2 and 3 of the accompanying drawings each show parts of a carrier strip,

Figure 2 showing the loading position and

Figure 3 showing the unloading position.

Figures 4 and 5 are edgewise views of the loaded strip showing respectively the slack and taut state, and

10 Figure 6 is a diagrammatic plan view of a conveyor device equipped with the new carrier strip.

Two carrier strips *a* and *b* each consist of two tapes *a1* and *a2* or *b1* and *b2*, of pliable material which are joined along spaced lengths *a3* or *b3*, while between these 15 lengths the two tapes are separable so as to form pockets *j* therebetween. Each of the strips *a* and *b* is passed between pairs of feed-control rollers *c*, *d*, *e*, *f*, by which it is moved in the direction of the arrows *x*. For simplicity's sake the strips have been assumed to move along 20 closed paths, but it will be readily appreciated that alternatively the path may be broken at suitable points to cause the strips to be fed from, or into, magazines.

Wire-ended components *g* are supplied periodically through a chute *h* and are to be discharged periodically 25 to a part *i* of an automatic assembly plant. The rollers *c* and *e* are positively driven, continuously or periodically, through gears *c1* or *e1*, while rollers *d* and *f* are braked by drum brakes *d1* and *f1*. As a result rollers *d* and *f* will lag behind rollers *c* and *e* respectively, so that the 30 pockets *j* will open under chute *h* to receive a wired element *g* and above part *i* to release such element. On the other hand the strip is taut between rollers *d* and *e*, thus holding elements *g* by the end wires *k* thereof.

Figures 2 to 6 illustrate an embodiment of the invention, in which cylindrical components *l*, for example wire-ended resistor elements, are loaded in the pockets *j* of the strip *a* in such manner that the strip will grasp the body of the element itself, and not only the wire ends thereof. In this case the strip, upon which a feeding 35 pull is exerted in the direction of the arrow *Y*, is, in order to effect the loading, grasped by the first pair of jaws *m* at the zone *a3* between the last previously loaded pocket *j* and the pocket *j2* into which the element *l* is to be introduced. A second pair of jaws *n* is arranged 40 to grip the next attachment zone, namely that between the pocket *j2* and the next following pocket *j3*, which is to be loaded after the loading of pocket *j2* has been completed. The arrangement is such, that the jaws *n*, after gripping the strip, are moved jointly towards the 45 jaws *m*, so as to shorten the distance longitudinally of the strip which is occupied by the pocket *j2*, thereby opening this pocket as shown in Figure 2. When this state has been reached, the element *l* is introduced axially into the pocket, which at that time surrounds it with 50 clearance as shown in Figure 4. When now the jaws *m* open, in the next step of the operation, the feeding pull *Y* is applied to the pocket *j2*. When, due to pull *Y*, the part of the tape containing the pocket *j2* is taut, the element *l* is now firmly held by the friction of the tape 55 as shown in Figure 5. Jaws *n* now return to their initial position, and jaws *m* open far enough to allow the loaded pocket to pass between them, whereafter the strip is arranged to move forward by one step by means of suitable indexing mechanism indicated at *o* in Figure 6; the tensioning means for applying the pull *Y* are indicated at *p* in Figure 6.

The unloading of the elements is effected in a very similar manner by means of two pairs of jaws *q* and *r* respectively as shown in Figure 3. While approaching the unloading point the strip is maintained taut by the tensioning means *p* previously referred to. The jaws *q* then engage the strip at the zone between the pocket *j4* to be unloaded and the next following

pocket *j*5, which has not yet reached the unloading position. The second set of jaws *r* similarly grasps the zone between the pocket *j*4 and the pocket *j*6 which has previously been unloaded, whereafter the jaws *r* are arranged to move a short distance towards the jaws *q*, thereby releasing the tension in the section of the strip containing the pocket *j*4. This pocket therefore will open by changing its shape from that shown in Figure 5 to that shown in Figure 4, whereupon the element *l* is free to drop out of the pocket as shown in Figure 3. The jaws are then open, and a further indexing mechanism *s*, which serves to move the next pocket into the unloading position, retightens the strip, whereafter the jaws *q* likewise release the strip and open sufficiently for the next loaded pocket *j*5 to enter the unloading position.

Figure 6 shows in diagrammatic form the arrangement of a machine incorporating the elements which are represented to a larger scale in Figures 2 and 3. The various jaws are in this embodiment assumed to be operated by hydraulic cylinders, while a further hydraulic cylinder *t* or *u* respectively serves for effecting the longitudinal movement of the jaws *n* and *r* in the direction of the feed of the carrier strip. *v* and *w* are supply and take-up spools for the strip although obviously, similarly as in Figure 1, a closed-loop circuit of the strip may be employed if preferred.

The invention may be carried out different in some details from the embodiments hereinabove described. Thus, while it has been assumed that the movement of the strip takes place in step-by-step fashion, the loading and unloading being effected while the strip is stationary, a continuous motion of the strip may alternatively be employed; in this case reciprocating carriages, in which the mechanism actuating the jaws *m* and *n* or *q* and *r* is carried, may move with the strip during the loading or unloading stage of each pocket and then return to engage the next pocket.

I claim:

1. Apparatus for feeding wire-ended components from a point of supply to a point of discharge, comprising a carrier strip formed of two tapes of flexible material secured to each other along spaced parallel transverse zones of attachment to form spaced open-ended pockets each adapted to accommodate and slightly larger than the circumference of a component, means for feeding said carrier strip with its transverse direction substantially vertical along a path including a feeding point and a discharge point, means for maintaining said strip under longitudinal tension at least between said feeding point and said discharge point, means at each said feeding point and said discharge point for gripping said strip at the two zones of attachment provided respectively at each side of a pocket and for shortening the distance between the zones thus gripped to open the pocket between

said gripped zones to permit at the supply point the insertion of a component from above and at the point of discharge the release of a component to drop below before releasing the strip for further movement.

2. An apparatus for use in the manufacture of electrical apparatus, comprising a flexible carrier strip formed of two parallel tapes of flexible material joined together along spaced parallel zones transverse to the longitudinal direction of the strip to form collapsible pockets between the two tapes of material, each pocket adapted to accommodate a wire-ended component respectively arranged in the individual pockets, said pockets being slightly larger than the circumference of said components so that said components are frictionally held in the pockets by the material of the tapes as long as a longitudinal pull is exerted upon the carrier strip, the wire ends of the components projecting through the open ends of the pockets.

3. A method of feeding wire-ended electrical components to a discharge point by means of a flexible belt having open-ended transverse tension-collapsible pockets, which comprises loading such pockets each with a component having a circumference smaller than the size of the pocket, feeding said flexible belt thus loaded with components in a taut condition and with the transverse direction of the strip arranged substantially vertically, along a substantially horizontal path above said discharge point, and releasing each component from its pocket, as it reaches said discharge point, by shortening the length of a section of the belt including the pocket containing the component to be released but not including any loaded pocket on its way to said discharge point.

4. In apparatus for the manufacture of electrical apparatus including at least one wire-ended component, means for releasing at a point of discharge from a moving pocketed carrier strip components loaded in pockets thereof, said releasing means comprising in combination means for guiding such strip past the point of discharge, with the transverse direction of the strip substantially vertical, two sets of gripping jaws for respectively gripping said strip at points spaced longitudinally of the strip at opposite sides of the discharge point, and means for closing said sets of jaws to grip the strip at opposite sides of a loaded pocket, and for relatively moving said closed set of jaws to shorten their longitudinal spacing and thus release a component, and for then re-opening said sets of jaws.
